UNITED STATES PATENT OFFICE.

ROBERT A. SMITH, OF MAHWAH, NEW JERSEY, ASSIGNOR TO SMITH & SERRELL, OF MAHWAH, NEW JERSEY, A COPARTNERSHIP CONSISTING OF SAID ROBERT A. SMITH AND JOHN J. SERRELL.

DRIVING KEY AND PROCESS OF FITTING THE SAME.

Application filed July 6, 1922. Serial No. 573,195.

To all whom it may concern:

Be it known that I, ROBERT A. SMITH, a citizen of the United States, and resident of Mahwah, Bergen County, State of New Jersey, have made a certain new and useful Invention Relating to Driving Keys and Processes of Fitting the Same, of which the following is a specification, taken in connection with the accompanying drawing, 10 which forms part of the same.

This application is a continuation in part of my copending application Ser. No. 484,094 filed July 12, 1921, that is, this case contains subject matter taken therefrom.

15 This invention relates especially to driving keys and processes of fitting the same for coupling shafts to other parts of machinery, the keys being provided with cutting edges or portions preferably on at least 20 one or more of the driving faces of the key and also in some cases on one or both intermediate longitudinal faces of the key so that when the key is forcibly driven into the usual rough key way in the shaft and other 25 cooperating parts these cutting edges cut or finish one or more of the inner surfaces of the key way to such an extent that the corresponding face of the key is forced or wedged against the same to give a wedging 30 closely fitting and secure driving connection between the parts. Especially where the key is to be withdrawn at relatively frequent intervals it is preferably thoroughly greased or oiled adjacent the cutting faces 35 before it is driven which prevents or minimizes the abrasion or undesirable cutting action which might otherwise occur between these strongly engaging metal faces. It is usually desirable to form such keys of hard- 40ened and tempered steel at least adjacent the head or forward cutting portion which may be advantageously ground to size after such heat treatment or otherwise accurately shaped so as to form the cutting edges or 45 portions which preferably have adjacent chip retaining recesses especially where several cutting edges are formed on the same face of the key so that each cutting edge can successively finish or cut off portions 50 of the key way face to more accurately finish the same. It is also advantageous to guide or align the head of the key while it is being driven and for this purpose a somewhat

narrower or smaller forward guiding aligning portion may be formed ahead of the 55 main cutting edges or portions so that the key is automatically guided or aligned as it is hammered or forced into the key way. It is also desirable in many cases to adjust the effective length of the key by cutting 60 off or removing parts of the same before or after it is driven into place and for this purpose a severable rear or driving end may be formed on the key end of relatively soft material which may be cut off by hack saws, 65 etc., or by having a hard driving end formed with breaking nicks or notches extending more or less around it at the desired intervals so that portions may be broken off either before or after the key is driven. 70

In the accompanying drawing showing in a somewhat diagrammatic way a number of illustrative keys for use in such processes:

Fig. 1 is a sectional view showing the use of such a key; and

Fig. 2 is an end view thereof.

Fig. 3 is an enlarged top view partly in section showing the key construction in greater detail; and

Figs. 4 to 6 are similar views showing 80 other illustrative forms of keys.

Fig. 7 is a side view showing another form of key and

Fig. 8 is a corresponding end view.

Fig. 9 is a side view showing still another 85 illustrative construction, and

Fig. 10 is an end view thereof.

As indicated in Figs. 1 and 2, the ordinary rough slotted or milled keyways 11, 14 may be formed in any desired way in the co-operating parts such as the shaft 12 and the flange and coupling member 15 for example. The self-fitting or cutting key 1 which may have one or more cutting edges such as 2, 3 on at least one of the driving faces of the key such as its upper or lower notched edges as indicated in Fig. 1 becomes active in resisting the torque between these two rotating members under service conditions; and if desired, both of these opposite driving faces 100 may be formed with one or more of such cutting edges 2, 3 so that when the key is forced into this slightly undersized keyway, these edges automatically cut their own slot of such size as to accurately accommodate or 105 fit the body 9 of the key. Of course the end

10 of the key may be beveled if desired so as to be driven home by a hammer or other means. It is also desirable to form such self-fitting cutting keys of tool steel or still 5 better of special tough strong steel, which is heat treated to harden and toughen the body of the key and leave the cutting edges in most effective condition. In many cases it is desirable to preliminarily or roughly form 10 these cutting edges and then after hardening and tempering the key, to grind or otherwise finish or straighten the key body, and in some cases to grind the cutting edges in proper relation thereto to get best results.

15 As is indicated in Fig. 3 one or more cutting edges such as 2, 3 may in many cases be advantageously formed on both of the opposing driving faces of the key, and each of these successively acting cutting edges 20 may be slightly larger so that each of them may remove a few thousandths of an inch from the corresponding face or edge of the keyway as the key is driven home. It is sometimes advantageous to have the final 25 cutting edge such as 3 formed so as to take only a light cut, this material being accommodated in a chip retainer recess such as 6 formed adjacent this cutting edge and extending inward, so as to give ample room to 30 produce the desired cutting angle for this edge. In some cases also one or more cutting edges such as 5 may be formed on one or both of the other faces of the key besides the driving faces thereof, although it is 35 usually better to have at least one of these inner and outer key faces flat so as to act somewhat more efficiently as a guide and aligning surface when the key is inserted. In some cases also the key body may have 40 a wedging action if the final cutting edge is slightly smaller than the adjacent driving face of the key, and as shown on an exaggerated scale in Fig. 3 the width of the portions 8 of the key adjacent the cutting edges 3 may be slightly smaller than 45 the corresponding driving faces 9; and the inclined or curved portion 7 joining these two faces may have a few thousandths of an inch or less difference so as to secure the 50 desired tightness of drive fit depending of course on the size of key employed.

Fig. 4 shows another illustrative key 21 which may have the opposing driving faces formed with cutting edges 19 adjacent the 55 front end or head of the key; and in some cases also a forward aligning guiding portion 18 having somewhat rounded or dulled edges of slightly less width may be formed ahead of these lateral cutting edges so as to 60 guide the key when inserted and during its first cutting movements. This guiding portion may be formed in some cases with forward cutting edges 17, if desired, and intermediate cutting edges 16 may be formed on 65 this guiding portion preferably on the up-

per face thereof. The upper face of the key proper may also be formed with a cutting edge 20 preferably longitudinally displaced from the lateral cutting edges 19 and these cutting edges may advantageously be formed 70 with cutting angles of about 75° as is indicated in connection with the cutting edges 19. Suitable chip retaining recesses such as 23 may be formed adjacent any or all of these cutting edges. It is in many cases 75 desirable to have the length of these self-fitting keys adjustable so that any suitable length can be cut or broken off from the standard length keys manufactured and sold; and for this purpose it is often advantageous to form angular breaking notches or 80 nicks such as 22 extending more or less completely around the key at intervals of a quarter or a half inch apart adjacent its rear driving end where it is struck by the hammer driving the key into the keyway. Such weakening breaking nicks or angular recesses or notches make it possible to break off one or more sections from the key before 85 or after it is started into the keyway; and the key may, for instance, be placed in a heavy vise with the desired amount projecting beyond one of these weakening nicks or 90 notches and then by striking the projecting end laterally with a heavy hammer it can be 95 broken off and the remaining end portion ground or otherwise smoothed up before driving the key home.

Fig. 5 shows another illustrative arrangement for making the key length adjustable 100 and as there shown, the self-fitting key may have a hardened head 32 comprising the cutting edges or portions and the guiding aligning portions of the key, while the opposite or rear driving end 33 of the key is left in 105 soft or annealed condition so that more or less of this end can be cut off by hack saws or otherwise removed before the key is driven into the keyway, and of course, if desired, a beveled portion such as 34 may be formed 110 to prevent undesirable spreading of the extreme driving end of this key where the upsetting forces are usually large. Such keys may have any suitable arrangement of cutting edges and, as indicated, the hardened 115 head 32 of the key may be provided with the cutting edges 39 on its opposite lateral or driving faces, any suitable chip recesses such as 40 being ground or otherwise formed adjacent these edges. In this case the upper 120 cutting edge 38 is shown as being formed somewhat ahead of the lateral cutting edges, which is somewhat more desirable in general practice since, as is usual, these main cutting edges remove five one-thousandths to 125 ten one-thousandths of an inch or so from the outer surface of the keyway which seems desirable for best results to make the driving and cutting action uniform. Under such conditions the cutting edge especially 130

when the cutting angle is not much less than 90° seems to automatically exert a considerable wedging action so as to force the head of the key down into forcible engagement 5 with the bottom of the keyway in the shaft which is usually fairly straight on this lower milled surface thus preventing or minimizing subsequent twisting or bending of the key during its driving which is of course undesirable. The key may as indicated be formed with a somewhat reduced forward aligning guiding portion having the lateral faces 37 and the upper face 36 which may be formed with sharp cutting edges such as 10 35, if desired.

Fig. 6 shows another illustrative self-fitting key 24 which may have a number of cutting edges 27, 28 and 29 on one or both of the driving faces 30, and also if desired such 20 cutting edges as 25 may be formed on one of the other faces of the key at right angles to these driving faces. These cutting edges are of course progressively larger so that each cutting edge removes part of the material as 25 the key is driven forward, and this is of course advantageous since the cutting edges are less likely to be broken or injured as the key is driven home. In some cases it is desirable to form the leading cutting edge with 30 a substantially parallel guiding or aligning face or member 26 adjacent the same, which somewhat promotes the desired lateral positioning of the key as it is driven into the rough keyway. Of course by having different 35 or oversized self-fitting keys of this character worn or loosened key connections can be refitted and tightened, and when initially connecting keyed parts the very considerable expense and time usually required 40 for accurate fitting and finishing is obviated. It seems desirable to make such oversized self-fitting keys about five one-thousandths or ten one-thousandths of an inch larger in each transverse direction where cutting action 45 takes place than the standard size self-fitting keys of this character, so that badly fitted or worn keyways can be effectively taken care of in this way, and where a self-fitting key has been repeatedly driven out 50 the parts may be tightly fitted and wedged apart by the use of such a special or oversize key. Where it is expected that such self-fitting keys are to be removed, especially where such removal takes place at relatively frequent 55 intervals it is quite desirable to heavily oil or grease the keys, especially at their forward portions, before driving them, effective lubrication preventing the abrasion or cutting action which otherwise sometimes tends to take place between the flat surfaces 60 of the keyway and the sides of the key back of its cutting edges where these faces are so strongly pressed together without lubrication. When properly lubricated, however, a 65 suitable self-fitting key may be driven out

and replaced a number of times with ordinary care without undesirably loosening the connection.

Figs. 7 and 8 show another illustrative form of self-fitting key in which a wedging 70 tapered portion or face 42 is formed on one of the longitudinal faces of the key, preferably on its outer face and this tapered portion may have the usual degree of taper of an eighth of an inch per foot for relatively 75 short hardened keys of this character, so as to fit in the keyway which may be cut with a similar taper. The key may be formed with one or more lateral cutting edges 49 and, if desired, a reduced forward aligning 80 or guiding portion 44 may be formed so as to provide a guiding face or member ahead of each of these cutting edges 49, and formed with lateral and top cutting edges 45, 46, if desired. With this arrangement 85 where the wedging upper surface 42 of the key is carried down to or adjacent the cutting edges 49 it is naturally somewhat narrower than these cutting edges 49 or the rearwardly extending lateral faces of the 90 key body 41. For this reason the tapered face between its edges 43 properly engages and cooperates with the tapering keyway originally formed in the shaft and cooperating part which promotes the accuracy of fit 95 between these parts.

Figs. 9 and 10 show another illustrative form of key in which the cutting edges are formed with a cutting angle of about 90° which cuts fairly well, although not quite 100 as easily in such materials, as a cutting angle of about 75° illustrated in connection with the other figures. This key 51 may have the lateral cutting edges 53 and the upper cutting edge 52 of such character and 105 where a forward aligning guiding portion such as 57 is formed so as to provide a guiding face or member ahead of each of these main cutting edges a chip recess such as 54 may be formed around the desired number 110 of faces of the key and this chip recess may be formed or finished by milling or grinding preferably with a round edged thin tool so as to form such a chip recess as 54 and simultaneously form the adjacent cutting edges which may thus be located at the same longitudinal point on the key. If desired, similar square or 90° cutting edges such as 55, 56 may be formed on the forward aligning 115 guiding portion of the key to take care of any projections or irregular portions of the key-way. As indicated in Fig. 9, the cutting head of this key may be suitably hardened while the other or rear driving end of the key may be left in soft or annealed condition so that more or less of this end can be cut off by hack saws or otherwise removed before the key is driven into a keyway as in the case of the Fig. 5 key. Fig. 10 also 120 illustrates the use of slightly rounded or 125

beveled corners or longitudinal edges 58 on these keys which are sometimes desirable to prevent the workmen cutting themselves on the sharply ground edges which are naturally formed in finishing the keys and also to reduce the undesirable cutting action on the metal which sometimes occurs with such sharp edges. These self-fitting keys have proved very successful under service conditions and careful tests made with such keys as compared with the ordinary keys which have been hand fitted with unusual care show that the self-fitting key allows considerably less yield between the parts under similar loads or forces so that a much greater degree of rigidity and strength of driving connection is thus secured while the long and expensive hand fitting of the usual keys is completely eliminated.

20 This invention has been described in connection with a number of illustrative embodiments, forms, proportions, orders of steps, arrangements, sizes and materials, to the details of which disclosure the invention 25 is not of course to be limited since what is claimed as new and what is desired to be secured by Letters Patent is set forth in the appended claims.

1. The process of fitting driving keys in 30 the rough keyways of shafts and cooperating parts, which comprises driving into such a keyway a rectangular sectioned key and simultaneously sizing or fitting at least two 35 rectangularly located inner surfaces of the keyway and tightly forcing and wedging into the sized keyway the adjacent body portion of the key.

2. The process of fitting driving keys in 40 the keyways of shafts and cooperating parts, which comprises driving into such a keyway a rectangular sectioned key and simultaneously sizing at least two rectangularly located inner surfaces of the keyway and 45 tightly forcing into the sized keyway the body portion of the key.

3. The process of fitting driving keys in 50 the rough keyways of shafts and cooperating parts, which comprises driving into such a keyway a rectangular sectioned key and simultaneously sizing or finishing at least several of the inner surfaces of the keyway by 55 cutting portions formed adjacent the forward end of the key and forcing and wedging into the sized keyway the adjacent body portions of the key.

4. The process of fitting driving keys in 60 the rough keyways of shafts and cooperating parts, which comprises driving into such a keyway a rectangular sectioned key and simultaneously sizing or finishing at least one 65 of the inner surfaces of the keyway by a cutting portion formed adjacent the forward end of the key and forcing and wedging into the sized keyway the adjacent body portions of the key.

5. The process of fitting driving keys in the rough keyways of shafts and cooperating parts, which comprises driving into such a keyway a rectangular sectioned key and simultaneously sizing or fitting the keyway, 70 forcing into the sized keyway the adjacent body portion of the key and also in removing undesirable parts of the rear end of the key to adjust its effective length.

6. The process of fitting driving keys in 75 the rough keyways of shafts and cooperating parts, which comprises driving into such a keyway a rectangular sectioned key and simultaneously sizing or fitting at least two 80 rectangularly located inner surfaces of the keyway and tightly forcing into the sized keyway the body portion of the key and also in removing undesirable parts of the rear end of the key to adjust its effective length.

85 7. The process of fitting driving keys in the rough keyways of shafts and cooperating parts, which comprises driving into such a keyway a rectangular sectioned key and simultaneously sizing or fitting at least two 90 inner surfaces of the keyway and tightly forcing into the sized keyway the body portion of the key and also in removing undesirable parts of the rear end of the key to adjust its length.

9. The process of fitting driving keys in 95 the keyways of shafts and cooperating parts, which comprises driving into such a keyway a rectangular sectioned key and simultaneously sizing at least two rectangularly located inner surfaces of the keyway and tightly forcing into the finished keyway the body portion of the key.

10. The process of fitting driving keys in 105 the rough keyways of shafts and cooperating parts, which comprises driving into such a keyway a rectangular sectioned key and simultaneously sizing or finishing at least several of the inner surfaces of the keyway by cutting portions formed adjacent the forward end of the key and forcing or wedging into the finished keyway the adjacent body portions of the key having at least as great width as such adjacent cutting portions.

110 11. The process of fitting driving keys in the rough keyways of shafts and cooperating parts, which comprises driving into such a keyway a rectangular sectioned key and simultaneously cutting and finishing at least 115 one of the driving faces of the keyway by a plurality of successively acting cutting edges 120

125 130

- formed on the forward part of the key and simultaneously keeping the front part of the key in alignment and tightly forcing or wedging the body of the key into the finished keyway to tightly connect the cooperating parts. 5
12. The process of fitting driving keys in the rough keyways of shafts and cooperating parts, which comprises driving into such 10 a keyway a polygonal sectioned key and simultaneously cutting and sizing at least one of the driving faces of the key and simultaneously keeping the key in alignment by a relatively narrower guiding aligning portion 15 ahead of the main cutting edge and tightly forcing the body of the key into the finished keyway to tightly connect the cooperating parts. 20
13. The process of fitting keys in the rough keyways of shafts and cooperating parts, which comprises driving into such a keyway a polygonal sectioned key and simultaneously cutting and sizing at least one of the faces of the keyway by a cutting 25 edge formed on the forward part of the key and tightly forcing the body of the key into the finished keyway to tightly connect the cooperating parts. 30
14. The process of fitting driving keys in the keyways of shafts and cooperating parts, which comprises driving into such a keyway a rectangular sectioned key and simultaneously sizing the keyway and forcing or wedging into the sized keyway the body 35 portions of the key to tightly connect the cooperating parts. 40
15. The process of fitting driving keys in the rough keyways of shafts and cooperating parts which comprises driving into such 45 a keyway a rectangular sectioned key having an oiled cutting head and simultaneously cutting and sizing at least one of the faces of the keyway and tightly forcing and wedging the body of the key into the finished keyway to tightly connect the cooperating parts and driving the key out of the keyway when the parts are to be disconnected. 50
16. The process of fitting driving keys in the rough keyways of shafts and cooperating parts which comprises driving into such a keyway a lubricated rectangular sectioned key and simultaneously cutting and sizing at least one of the faces of the keyway and tightly forcing the body of the key into the finished keyway to connect the cooperating parts. 55
17. In self-fitting driving keys, a key having a hardened cutting head comprising on 60 at least one of its two opposite driving faces and on its outer intermediate longitudinal face a front aligning guiding member and a cooperating rearwardly located main cutting edge projecting outward further than
- said guiding member to wedge said key as 65 it is driven longitudinally into the keyway. 70
18. In self-fitting keys, a key having a cutting head comprising a wedging cutting edge to wedge said key as it is driven longitudinally into the keyway. 75
19. In self-fitting driving keys, a key having a hardened cutting head and a relatively soft driving end adapted to be cut off to shorten the length of the key, said cutting head comprising a cutting edge on at least 80 one of its two opposite driving faces and on an intermediate longitudinal face. 85
20. In self-fitting driving keys, a key having a hardened cutting head and a relatively soft driving end adapted to be cut off to shorten the length of the key, said cutting head comprising a cutting edge. 90
21. In self-fitting driving keys, a key having a hardened cutting head and a relatively soft driving end adapted to be cut off to shorten the length of the key, said cutting head comprising a cutting edge on at least 95 one of its two opposite driving faces. 100
22. In self-fitting keys, a key having a cutting head comprising a hard cutting edge and a relatively soft driving end. 105
23. In self-fitting driving keys, a rectangular sectioned key having on each of its two opposite driving faces and on at least 110 the outer intermediate longitudinal face a cutting edge and a front guiding aligning member projecting outward less than said cutting edge and a chip retainer recess between each of said cutting edges and the cooperating guiding members. 115
24. In self-fitting driving keys, a rectangular sectioned key having on each of its two opposite driving faces and on at least 120 an intermediate longitudinal face a cutting edge and a front guiding aligning member projecting outward less than said cutting edge. 125
25. In self-fitting driving keys, a key having on at least one of its two opposite driving faces and on an intermediate longitudinal face a cutting edge and a chip retainer recess adjacent each of said cutting edges. 130
26. In self-fitting driving keys, a key having on at least one of its two opposite driving faces and on an intermediate longitudinal face a cutting edge. 135
27. In self-fitting driving keys, a rectangular sectioned key having on its outer longitudinal face a cutting edge having a cutting angle of about 75° or more and an adjacent chip recess and a cooperating cutting edge on at least one of the lateral driving faces of the key. 140
28. In self-fitting keys, a key having a flat side and having on an opposing longitudinal face a cutting edge having a cutting angle of about 75° or more to produce a

- lateral wedging action toward said flat side of the key simultaneously with the cutting action of said cutting edge.
29. In self-fitting driving keys a rectangular sectioned key having on a longitudinal face a cutting edge having such a large cutting angle as to produce a lateral wedging action simultaneously with the cutting action of said cutting edge.
- 10 30. In self-fitting driving keys, a key having a plurality of cutting edges on each one of several of its adjacent faces and having a front guiding aligning member projecting outward less than said cutting edges and a chip retainer recess between said guiding member and said cutting edges.
- 20 31. In self-fitting keys, a rectangular sectioned key having a cutting edge on each one of several of its adjacent faces and having a forwardly extending front guiding member.
32. In self-fitting keys, a rectangular sectioned key having a cutting edge on each one of several of its adjacent faces.
- 25 33. In self-fitting driving keys, a rectangular sectioned key having on each one of several of its adjacent faces a cutting edge and an adjacent chip retainer recess.
- 30 34. In self-fitting driving keys, a rectangular sectioned key of hardened steel having on each of its opposite driving faces a plurality of cutting edges of progressively increasing width to produce a fit as the key is driven or forced into a rough finished key-35 way.
35. In self-fitting driving keys, a key having on one of its faces a plurality of cutting edges at progressively increasing distances from the opposing face.
- 40 36. In self-fitting driving keys, a substantially rectangular sectioned key formed on several of its faces with a plurality of successively acting hardened cutting edges and with a chip retainer recess between said 45 cutting edges.
37. In self-fitting driving keys, a substantially rectangular sectioned key formed on one of its faces with a plurality of cutting edges and with a chip retainer recess 50 between said cutting edges.
38. In self-fitting driving keys, a key formed with a plurality of successively acting hardened cutting edges and with a chip retainer recess between said cutting edges.
39. In self-fitting keys, a substantially 55 rectangular sectioned key formed on its opposing driving faces with a hardened cutting edge to resize the keyway as the key is forced into the same.
40. In self-fitting driving keys, a substantially 60 rectangular sectioned key comprising a cutting edge formed on one of its faces to size the corresponding side of the keyway as the key is forced into the same.
41. In self-fitting driving keys, a key 65 having on each of its two opposite driving faces a cutting edge and a front guiding aligning member projecting outward less than said cutting edge and a chip retainer recess between said guiding member and 70 said cutting edge.
42. In self-fitting driving keys, a key having on one of its faces a cutting edge and a front guiding aligning member projecting outward less than said cutting edge and a chip retainer recess between said guiding member and said cutting edge.
43. In self-fitting driving keys, a key having on one of its faces a cutting edge and a front guiding member in front of and 80 projecting outward less than said cutting edge.
44. In self-fitting keys, a key having on one of its faces a cutting edge and a front guiding member.
45. In self-fitting keys, a rectangular sectioned key having on each one of several of its faces a cutting edge and a forwardly extending front guiding member.
46. In self-fitting keys, a rectangular sectioned key having on one of its faces a cutting edge and an adjacent chip retainer recess.
47. In self-fitting keys, a substantially 90 rectangular sectioned key comprising a cutting edge formed on one of its faces to produce a tight fit as the key is forced into the keyway.

ROBERT A. SMITH
